CLAIM

The ornamental design for a glass with wedge, as shown and described.

DESCRIPTION

FIG. 1 is a top, front perspective view of a glass with wedge;

FIG. 2 is a front view thereof;

FIG. 3 is a back view thereof;

FIG. 4 is a right-side view thereof;

FIG. 5 is a left-side view thereof;

FIG. 6 is a top view thereof; and,

FIG. 7 is a bottom view thereof.

In the drawings, the evenly dashed broken lines show portions of the glass with wedge that form no part of the claimed design. The dot-dash broken lines define the bounds of the claimed design and form no part thereof.
